CLAIM

The ornamental design for a produce container, as shown and described.

DESCRIPTION

FIG. 1 is a front, top and right side perspective view of a produce container once constructed in three dimensions; FIG. 2 is a top plan view of the produce container of FIG. 1;

FIG. 3 is a bottom plan view of the produce container of FIG. 1;

FIG. 4 is a front elevation view of the produce container of FIG. 1;

FIG. 5 is a rear elevation view of the produce container of FIG. 1;

FIG. 6 is a left side elevation view of the produce container of FIG. 1;

FIG. 7 is a right side elevation view of the produce container of FIG. 1;

FIG. 8 is a front, bottom and right perspective view of the produce container of FIG. 1;

FIG. 9 is a front, top and left perspective view of the produce container of FIG. 1;

FIG. 10 is a front, top and right side perspective view of a produce container before being constructed in three dimensions;

FIG. 11 is a top plan view of the produce container of FIG. 10;

FIG. 12 is a bottom plan view of the produce container of FIG. 10;

FIG. 13 is a front elevation view of the produce container of FIG. 10;

FIG. 14 is a rear elevation view of the produce container of FIG. 10;

FIG. 15 is a left side elevation view of the produce container of FIG. 10;

FIG. 16 is a right side elevation view of the produce container of FIGS. 10; and,

FIG. 17 is a front, bottom and right perspective view of the produce container of FIG. 10.
